FLIGHT LUGGAGE BAG

Walter Bialo, 32—33 47th Ave., Long Island City,
N.Y. 11103

Filed Mar. 16, 1970, Ser. No. 21,907

Term of patent 14 years

Int. Cl. D3—01

U.S. Cl. D87—5

FIG. 1

FIG. 2

FIG. 4

FIG. 5

FIG. 3

FIG. 1 is a front elevational view of a flight luggage bag embodying my new design;

FIG. 2 is a top plan view thereof;

FIG. 3 is a side elevational view thereof, the other side being similar;

FIG. 4 is a rear elevational view thereof; and,

FIG. 5 is a bottom plan view thereof.

I claim:

The ornamental design for a flight luggage bag, as shown and described.
